FIGURE 4A

FIGURE 5D

FIG. 1 $\oplus$

FIG. 1 is a top front perspective view of a portable beverage dispenser showing my new design.

FIG. 2 is a front elevational view thereof.

FIG. 3 is a rear elevational view thereof.

FIG. 4 is a side elevational view thereof.

FIG. 5 is a plan view thereof.

FIG. 6 is a bottom plan view thereof.

The dominant feature of my design resides in the enclosure apart from the discharge spouts and bottle.

I claim:

The ornamental design for a portable beverage dispenser, substantially as shown and described.
